UNITED STATES PATENT OFFICE.

WILLIAM J. KERR, OF SMETHPORT, PENNSYLVANIA.

TOP.

1,338,574.

Specification of Letters Patent.

Patented Apr. 27, 1920.

Application filed October 13, 1919. Serial No. 330,208.

To all whom it may concern:

Be it known that I, WILLIAM J. KERR, a citizen of the United States, residing at Smethport, in the county of McKean and State of Pennsylvania, have invented certain new and useful Improvements in Tops; and I do declare the following to be a full, clear, and exact description of the invention, such as will enable others skilled in the art to which it appertains to make and use the same.

My invention relates to games and toys and more particularly to a top, and the principal object of the invention is to provide a simple and inexpensive device of this class by whose use very pleasing optical effects may be produced, both while the top is operating in a horizontal position or traveling along a cord or like track.

20 In carrying out the above end, I make use of a number of novel features of construction and a unique combination of parts, as hereinafter described and claimed, and shown in the accompanying drawing.

25 Figure 1 is a vertical section of a top constructed in accordance with my invention.

Fig. 2 is a top plan view of the device shown in Fig. 1.

30 Fig. 3 is a vertical section showing a slightly different form of the device.

In the drawing above briefly described, the numeral 1 designates a casing preferably stamped from sheet metal, said casing being open at its upper end and having a circular side wall 2. Rising from the bottom of the casing 1 is a central staff 3 which may be attached thereto in any preferred manner. This staff is in most cases tubular and is provided with a conical upper end 4 forming 35 both an internal and an external bearing center. A thimble or hub 5 loosely surrounds the staff 3 and is equipped with a conical upper end 6 likewise forming internal and external bearing centers. The internal center of the thimble 5 rests upon the outermost center of the staff 3 and the thimble is thus supported for rotation with little friction. The internal bearing center of the staff 3 preferably rests on a center 7 on the 40 upper end of a stem 8 which is receivable loosely in said staff, and although not essential, said stem is by preference equipped with an enlarged lower end 9 having a projecting bearing center 10. The thimble 5 carries a rather heavy spinning disk 11 and 45 when said thimble and disk are spun, for

instance by a suitable top string 12, they will operate for a great length of time, since little friction exists. When the casing 1 is supported by the stem 8 loosely received in 60 the central staff 3, as shown, rotation of the disk 11 and its thimble 5 also cause rotation of said staff and casing, and such rotation will continue whether the stem 8 be held in the user's hand or allowed to stand upright 65 on the center 10. Furthermore, if the top is spun while holding the stem in one hand and the entire device is then dropped to the floor, the several parts will remain in proper relation with each other and will continue 70 to rotate. Furthermore, after starting the disk 11 rotating, the top may be inverted so that said disk and its thimble 5 will drop from the remainder of the device and may spin in an inverted position. 75

In connection with the features above described, I employ a ring-like disk 13 resting loosely on the spinning disk 11, with the hub or thimble 5 of the latter passing loosely through the central opening 14 of 80 said ring-like disk. This disk is adapted for running contact with the circular wall 2 of the casing 1 and may be ornamented in any suitable way, and when the device is operated, very pleasing effects will be produced. I have found that when the disk 13 is ornamented in the manner shown, some figures thereof appear to travel in one direction while others seem to move reversely, certain of such figures in the meantime appearing as if rotating upon individual centers as well as shifting radially. The disk in question is moved against the wall 2 by centrifugal force and does not seem to roll smoothly around such wall, but rather 85 jumps inwardly and outwardly, contacting intermittently with said wall. These movements of disk and suitable ornamentation thereof serve to produce the effects above pointed out. 90

During operation of the device, an annular stop flange 15 on the upper end of the thimble 5, prevents any possibility of the disk 13 flying from said thimble. This flange comes into play principally when the parts 5, 13 and 11 are operating in an inverted position or when the casing 1 is traveling along a cord or like track, for which purpose said casing is provided with an external circumferential groove 16. 105

In some forms of the device, instead of providing the stem 8 shown in Fig. 1, I may 110

employ a shorter stem 8^a fitting either fixedly or removably in the staff 3 and provided at its lower end with a bearing center 10^a, as seen in Fig. 3.

5 All forms of the device are simple and inexpensive yet have proven to be highly entertaining. Since probably the best results are obtained from the details shown, they may well be followed. I wish it understood however that within the scope of 10 the invention as claimed, numerous minor changes may be made.

I claim:

1. A top comprising a casing open at its 15 upper end and provided with a circular side wall, a central staff rising from the bottom of said casing and having a bearing on its upper end, a thimble loosely surrounding said staff and resting rotatably on said 20 bearing, a spinning disk carried by said thimble, and a loose disk adapted to be supported by said spinning disk for contact with said circular wall.

2. A top comprising a casing open at its 25 upper end and provided with a circular side wall, a central staff rising from the bottom of said casing and provided at its upper end with a bearing center, a thimble loosely and removably surrounding said staff and having 30 both external and internal bearing centers, the latter engaging said bearing center of said staff, a spinning disk carried by said thimble, and a loose disk adapted to be supported by said spinning disk for contact 35 with said circular wall.

3. A top comprising a casing open at its 40 upper end and provided with a circular side wall, a central tubular staff rising from the bottom of said casing and having a closed upper end provided with both external and internal bearing centers, a thimble loosely surrounding said staff and resting on said external bearing center, a stem for loose reception in said staff and having a bearing 45 center upon which said internal center is adapted to rest, a spinning disk carried by

said thimble, and a loose disk adapted to be supported by said spinning disk for contact with said circular wall.

4. A top comprising a staff having a 50 bearing center at its upper end, a thimble loosely surrounding said staff and resting on said center, a spinning disk carried by said thimble, a ring-like disk through whose opening said thimble extends loosely, and an annular stop flange on said thimble above said spinning disk to retain said ring-like disk against accidental displacement.

5. A structure as specified in claim 4; 60 said thimble having at its upper end an external bearing center whereby it may stand and rotate in an inverted position.

6. A top comprising a casing having a circular side wall provided with a circumferential groove in its outer side adapted to 65 receive a cord or like track, and a spinning disk rotatably mounted in said casing.

7. A top comprising a casing having an open upper end and a circular side wall provided with an external circumferential 70 groove adapted to travel on a cord or like track, a spinning disk mounted in said casing and having a central hub portion, and a loose disk rotatably supported by said spinning disk for contact with said circular 75 wall.

8. A top comprising a casing having an open upper end and a circular side wall provided with an external circumferential 80 groove adapted to travel on a cord or like track, a spinning disk mounted rotatably in said casing and having a central hub, a ring-like disk through whose opening said hub extends loosely, said ring-like disk resting on said spinning disk and being adapted 85 for contact with said circular wall, and an annular flange on said hub to prevent accidental displacement of said ring-like disk.

In testimony whereof I have hereunto set my hand.

WILLIAM J. KERR.
